UNITED STATES PATENT OFFICE.

ERNEST O. FREDERICS, OF NEW YORK, N. Y., ASSIGNOR TO E. FREDERICS, INC., OF NEW YORK, N. Y., A CORPORATION OF NEW YORK.

SHIELD.

1,426,373.

Specification of Letters Patent. Patented Aug. 22, 1922.

Application filed August 2, 1921. Serial No. 489,209.

To all whom it may concern:

Be it known that I, ERNEST O. FREDERICS, residing at New York, in the county and State of New York, have invented certain 5 new and useful Improvements in Shields, of which the following is a specification.

This invention relates to an improvement in protecting devices or shields, and the prime object of the invention is to provide 10 a new and improved device adapted to protect the scalp of a person whose hair is being subjected to a heating or steaming operation, such for instance, as when the hair on the head is subjected to what is 15 known as a "permanent waving operation."

Other objects and aims of the invention, more or less specific than those referred to above, will be in part obvious and in part 20 pointed out in the course of the following description of the elements, combinations, arrangements of parts and applications of principles, constituting the invention; and the scope of protection contemplated will be indicated in the appended claim.

25 In the accompanying drawing, wherein I have illustrated a preferred form of embodiment of my invention:

Figure 1 is a plan view of one embodiment of my invention.

30 Figure 2 is a sectional view thereof, taken on the line 2-2 of Figure 1.

Figure 3 is a plan view of a modified form of my invention.

Figure 4 is a sectional view, taken on the 35 line 4-4 of Figure 3; and

Figure 5 is a view in elevation, partly in section, showing the manner in which my improved shield is employed in actual practice.

40 Figure 6 is a side view of a shield in use with a strand of hair introduced therethrough, the radial fingers being in flexed position, the flexure being somewhat exaggerated.

45 Figure 7 is a sectional view of the shield with the fingers in flexed position, as shown in Figure 6.

50 Similar reference characters refer to similar parts in the several views of the drawing.

Before proceeding with a description of the structural features of my invention, it may here be noted that in the operation of permanent hair waving it is customary to 55 divide the hair into several independent

strands, and to wind each of said strands from the root upward, upon a metallic curler, to place upon each wound strand a moistened hair treating device, over which is positioned an electric heater.

60

During the operation of the electric heaters steam is generated from the moistened hair treating ingredient, and which steam if allowed freely to escape from the hair waving device toward the head of the subject, if not taken care of, will burn or scald the head of the subject being treated.

65

The object of the present invention, therefore, is to provide a shield of such construction that it may be readily positioned about 70 the coiled hair, and which will afford a complete protection to the scalp of the subject whose hair is being treated.

Another object of the present invention is to provide a shield of such construction 75 that it may be readily positioned about a strand of hair, and that it may be flexed so as to bear firmly against such strand and thereby to anchor the shield against movement relative thereto, in order to afford complete protection to the wearer.

80

Referring now to the drawing, the reference numeral 1 denotes a disk, preferably composed of a fibrous material, commonly called fibre, although it is understood that other suitable materials may be substituted therefor such as felt, said disk being provided at its central portion with an aperture 2. Extending in radial directions from said aperture 2, are slits 3.

90

By the construction outlined, the disc may be considered to be in the form of a ring or annulus, having a plurality of radial members, defined by the slits. These radial members extend from the inner margin of the 95 ring and the ends define the central aperture. When not in use, the radial members lie in the same plane as the ring but owing to the properties of the fibre of which the ring is made, the members which will be seen to be 100 of somewhat triangular shape, are susceptible of flexure about their bases which lie on the arc of the circle forming the inner margin of the ring. When the ends of the radial members are flexed out of the plane of 105 the ring, it will be understood, of course, that the central aperture bounded by the ends will be increased slightly in size, so that the shield is capable of having inserted through it a strand of hair of somewhat 110

larger diameter than the diameter of the aperture. By this arrangement of parts, the shield has a strand introduced through the central aperture, and thereby the ends of the 5 radial members are flexed slightly. The ends accordingly bear firmly against the strand and anchor the shield securely in position, so that there is no possibility that the shield will slip along the strand into contact 10 with the scalp. The manner in which the shield is held in position along the strand by the radial members being flexed, is clearly shown in Figures 6 and 7.

It will be understood, of course, that the 15 shield must be of heat-resistant material, and at the same time, of a fair degree of elasticity so that the ends of the radial members will not be permanently bent out of the plane of the ring by continued use. Again 20 it is necessary that the members be flexible so that the shield may be readily adjusted in position.

It is further to be understood that while the shield is of heat resistant material so as 25 to protect the scalp from escaping steam, it is important that it be held securely in position on the strand since it is heated up by the escaping steam and may reach a temperature which would produce discomfort or 30 even pain if allowed to touch the scalp. By the use of fibrous material in the form I have shown, the shield is anchored securely in position and there is no possibility of the shield slipping down along the strand into contact 35 with the scalp.

In Figures 1 and 2 I have shown the slits as being located at right angles to each other, and in Figures 3 and 4 I have shown said slits as being located at a greater angle from 40 each other, it being understood, of course, that the number of slits extending from said aperture may be varied at will.

It will be noted from an examination of Figure 5 of the drawing, that when the hair

is wound upon the curler, the shield may be 45 inserted over said coiled hair, and that when the same has been placed in position near the scalp of the subject, the portions 4 of the shield, separated by the radially extending slits, can be placed in such position as to form 50 a complete shield for the scalp adjacent the roots of the hair comprising the strand wound upon the curler. In other words, the shield will adjust itself upon the scalp of the subject so as to prevent any escaping 55 steam from scalding the hair of the subject.

As many changes could be made in this construction without departing from the scope of the following claim, it is intended 60 that all matter contained in the above description or shown in the accompanying drawing shall be interpreted as illustrative only and not in a limiting sense.

Having thus described my invention what I claim as new and desire to secure by Letters Patent is:

A protective shield comprising an annular piece of fibrous material having a plurality of independent members spaced apart and projecting radially from the inner margin 70 thereof, the ends of said members being formed so as to bound a substantially circular aperture, said members being flexible so as to permit of a flexure out of the plane of said shield whereby to permit the introduction through said aperture of a strand of hair of greater diameter than said aperture, and said ends being adapted to bear firmly against said strand when said members are in flexed position, whereby to hold said 75 shield against movement relative to said strand.

In testimony whereof, I affix my signature in the presence of two witnesses.

ERNEST O. FREDERICKS.
